UNITED STATES PATENT OFFICE.

HUGH ROBT. McDONALD, OF VIRGINIA, MINNESOTA.

MAGNETIC TOY.

Application filed March 3, 1923. Serial No. 622,616.

This invention appertains to an improved toy of a novel and instructive character which, in addition to affording amusement, also provides convenient means of instruction in the principles of magnetism.

As an essential object, the invention further contemplates the provision of a magic toy in which a floating figure, such as a fish or other water-inhabitant, is directed 10 through the execution of a series of maneuvers in a body of water by the apparently mystic influence of a magician's wand.

Specifically, the invention consists in a magnetized figure arranged to float in a 15 bowl, or other receptacle filled with water, and made to balance with the specific gravity of the water so that the least attraction will cause it to move up or down in the water; a magnetized stick or wand being 20 employed to attract or repel the figure from without the bowl, the magnetic influence of the wand being transmitted through the interposing substance of the bowl.

The invention further consists in the novel 25 construction and arrangement of the several parts hereinafter set forth and described, reference being had to the accompanying drawing forming part of this specification and in which similar characters of reference 30 indicate corresponding parts in all the figures.

Figure 1 is a view representing the invention as embodied in a toy fish, the fish bowl being shown in section.

Figure 2 represents a quarter section of the fish bowl in which is indicated the up and down, or bobbling movement, of the figure as effected by the waving of the wand.

Figure 3 is a somewhat similar view in 40 which, however, is indicated the manner of repelling the figure by the reversing of the wand.

Figure 4 is a vertical central section taken longitudinally of the body of the figure and 45 illustrating the manner of arranging the magnet and fish-tail therein, and

Figure 5 is a longitudinal sectional view of the magnetic wand.

In the specific embodiment herein 50 described, the invention contemplates the provision of a figured body 10 preferably formed to simulate a gold fish although any other object, such as a water-bug, may be used instead, if so desired. From a point 55 adjacent the mouth of the fish a hole 11 is

drilled through the body 10 and terminates at the back of the body, close to the tail 12, as shown. Disposed in the hole and thus extending lengthwise of the body of the fish is a round permanent magnet 13. Above 60 the rear end of the magnet the body 10 is provided with a vertically extending slot 14 in which is engaged the attaching stem 15 of the fish-tail. The tail is formed from rubber and is flexible, being serviceable in 65 steering the fish besides adding to the life-like appearance of the same as it moves through the water; the flexibility of the tail permitting it to move to either side of the body.

When placed in a suitable bowl or container 16 of water the fish, which is made to balance to a hair's breadth as hereinafter explained, is susceptible to the least attraction of the magnetic wand 17 and may be 70 caused to bobble up and down in the bowl, back up or move ahead, turn around, and execute various other maneuvers under the magnetic influence of the magician's wand. This wand is made from a straight piece of 75 steel that will retain magnetism to a high degree and is charged permanently with magnetism so that the north polarity is at one end of the wand and the south polarity at the other end. To prevent impairment 80 of the wand magnet 17, the latter may be coated with a protective covering of paint or varnish, as shown at 18.

In connection with the operation of the invention it will be observed that as the fish 85 contains a smaller magnet, the north polarity end of which has a mutual attraction for the south polarity end of the wand and since, also, there exists a like mutual attraction between the north polarity end of the wand 90 and the south polarity end of the magnet in the fish, the wand may be used to either attract or repel the fish. When one end of the wand is held a few inches or less from the fish, as in Figure 1, the fish will be attracted to it, the particular end of the fish 95 attracted depending on which end of the wand is presented. As the north and south polarity ends of the wand serve to attract the fish only when respectively opposed to the south and north polarity ends of the fish-magnet, being unlike poles, the reversing of the wand so as to bring like poles of the magnets into opposition will on the other hand serve to repel the fish which may thus 100 105 110

- be made to go forward, as in Figure 3, or caused to back up, or turn around by movement of the wand. The bobbling of the fish is accomplished by drawing the fish up close to the wand and then moving the latter in a bobbling manner, either up or down as indicated in the full and dotted line structure of Figure 2, or in a sidewise direction; the fish necessarily imitating the movements of the wand though the two be separated by the wall of the fish bowl which is preferably of glass or other non-magnetic substance through which the magnetic influence is readily transmitted.
- 15 The specific gravity of the fish is made as nearly equal to that of water as possible, and made permanent, except perhaps that it may be just a shade heavier than the water. With this end in view the body 10 is preferably constructed of hard wood and boiled in linseed oil which is absorbed in sufficient quantity to render the body water-proof so that it may not become water logged and have its specific gravity changed thereby. A suitable coating 19 of paint and varnish is then applied to the body to give it a finishing touch; the tail 12 being also provided with a light coating to prevent its deterioration.
- 20 The fish can be made to balance itself partway between the top and bottom of the bowl or container 16 by adding salt in the water which adds to the specific gravity of the latter. The tendency of the fish to remain submerged as described also gives it a realistic touch enhancing its lifelike appearance.
- 25 If left alone in the water, the fish acts as a compass by heading north and south. By reason of its magnetic property it will invariably assume this position when uninfluenced by the magnetic wand and if placed in

the water facing north will turn and face south of its own accord.

From the foregoing it will be seen that the invention not only provides an enjoyable and fun-furnishing toy of a mystic character to the uninitiated but also a device having an educational value in many respects and embodying means of utilizing the principles of magnetism in an instructive and helpful manner.

Having thus described my invention, what I claim as new and desire to secure by Letters Patent is:

1. A magnetic toy comprising a buoyant figure adapted to float in a body of water, a magnetized magician's wand for directing the said figure through various maneuvers, and a magnet extending lengthwise through a submerged portion of the said figure but having the unlike poles exposed at relatively opposite ends of the figure whereby the said wand may be used to attract, repel, or otherwise influence either end of the said figure, said magnet being adjacent the bottom of the figure and centrally of its opposite sides so that it tends to stabilize and hold the figure upright in the water.

2. A magnetic toy comprising a magnetized figure adapted to float in a body of water and comprising a body of buoyant material having an opening extending lengthwise through a lower longitudinal portion of the said body and having a vertically extending slot at one end, a magnet extending lengthwise through the said opening with its opposite ends exposed at the terminals of the opening, and a tail of flexible rubber having an attaching stem engaged in the said slot of the said body.

In testimony whereof I affix my signature.

HUGH ROBT. McDONALD.
